(No Model.)

T. ANGELL.
GAS REGULATOR.

No. 310,240.

Patented Jan. 6, 1885.

UNITED STATES PATENT OFFICE.

THOMAS ANGELL, OF BROOKLYN, NEW YORK.

GAS-REGULATOR.

SPECIFICATION forming part of Letters Patent No. 310,240, dated January 6, 1885.

Application filed June 23, 1884. (No model.)

To all whom it may concern:

Be it known that I, THOMAS ANGELL, of Brooklyn, in the county of Kings and State of New York, have invented an Improvement in 5 Gas-Regulators, of which the following is a specification.

Gas-regulators have been made in which the valve that regulates the admission of gas is connected with an inverted cup, the edges of 10 which pass into an annular holder containing mercury. The parts, however, are constructed in such a manner that the gas flows through the chamber within the inverted cup, and there is risk of accumulation of water and 15 other products of condensation in the said chamber. Besides this, the gas-regulator occupies so much space between the meter and the pipes in the building that changes are often required for allowing the regulator to be introduced.

In my improvement the inlet-pipe for the gas is in line with the outlet-pipe, and there is but little space occupied, so that usually the regulator can be introduced by simply 25 springing the pipes apart. The regulator is at one side of the couplings, and it is constructed so that the gas passes from the valve directly to the discharge-chamber through a valve-seat, which is screwed into the partition, and is, with the bridge that guides the valve-stem, removable upwardly, so that the parts are easily cleaned, and the gas-pipe connections are not disturbed.

In the drawings, Figure 1 is a vertical section of the regulator, and Fig. 2 is a plan with the cover and part of the inverted cup removed.

The cylindrical case A is made with a lateral double chamber passing off from the center of the case A. The diaphragm or partition B is between the chambers c and d, and within the lateral case E, and this case E projects beyond the case A a sufficient distance to receive the coupling f, that connects the 40 regulator to the meter, and the coupling g, that connects the regulator to the pipes of the building. These two couplings are in line with each other, so that the connection for the regulator can be made by springing the pipes apart a sufficient distance for introducing the 45

regulator-couplings. The couplings f and g are screwed directly into the metal of the case E, and can be removed so as to introduce whatever size of coupling may fit the unions upon the meter and pipe, respectively, thus allowing for fitting the same regulator upon any meter-pipes by simply changing the couplings f and g; and as these couplings screw directly into the top and bottom plates of the case E, and as these plates extend all around the holes 55 into which the couplings screw, said holes can be made larger or smaller to suit different couplings without changing any of the parts of the regulator, and the couplings can be introduced in a very small space and lessen the 60 distance that the pipes have to be sprung apart to introduce the regulator. The diaphragm B completely separates the chambers c and d, except that in line with the center of the case A there is an opening, into which is screwed 65 the ring-seat h for the valve k. The stem i of this valve k passes through and is guided by the bridge l, that rises above the valve-seat, and this stem passes through the center of the inverted cup m, and it is secured thereto and 70 adjusted by the lock-nuts n upon such stem i. The inverted cup m is preferably made of thin sheet metal, and its cylindrical rim is within the annular trough containing mercury at o. The dams p and q are concentric within the 75 case A, and the dam p forms one side of the annular mercury-trough. The dam q extends up to near the under surface of the inverted cup m, and its object is to catch any mercury 80 that may be spilled over from the trough o, and prevent it passing down into the meter, also to lessen the opportunity for gases or watery vapors to pass into and circulate through the chamber below the inverted cup m. The 85 gases pass from the inlet-coupling f along 90 through the chamber c, and through the valve-seat, and then directly off by the chamber d to the coupling g and pipe. The air and gases inside the inverted cup remain almost quiescent, but they are subject to fluctuations in 95 the pressure. When the burners are shut off and the gas accumulates in the chamber d, the inverted cup is lifted and the valve k closed, or nearly so. When the pressure in the chamber d lessens in consequence of the burners 100

being opened, the inverted cup descends and opens the supply-valve in proportion to the amount of gas that is being consumed. Should there be any water or condensation in the 5 pipes of the building, or in the gas-regulator, it passes directly through the regulator and into the meter, and cannot accumulate in the regulator or obstruct the flow of gas, and no plug or cock to draw off such accumulation is 10 required.

A cover, *s*, may be applied to the case *A* of the regulator to exclude foreign substances.

I do not claim a gas-regulator with a lateral case containing a partition with a valve-seat. 15 In some of the regulators of this character the valve has to be removed downwardly and the inverted cup upwardly. In other cases the seat was removable, but not easy of access, or in the partition. In consequence of the 20 valve-seat being provided with the bridge *l*, that extends upwardly and guides the stem, the seat, which otherwise would be difficult of access, can be unscrewed by means of the bridge, and the valve-seat and valve are removable upwardly after the inverted cup has 25 been taken off, so that the regulator only requires to be opened on top in obtaining access to all the parts.

I claim as my invention—

1. The combination, with the case *A*, of a 30 lateral case, *E*, with a partition in it, an upwardly-projecting bridge, and a valve-seat screwed into an opening in such partition, a valve and stem, an inverted cup attached to and removable from the valve-stem, an annular mercury-trough within the case *A*, and a 35 dam, also within said case, whereby the valve and its seat may be removed after the inverted cup has been taken off the stem, substantially as specified.

2. In combination with the gas-regulator and lateral case *E*, having a partition and valve-seat, the removable and changeable couplings *f* and *g*, in line with each other, and screwed into openings in the flat top and 45 bottom plates of such case *E*, substantially as set forth.

Signed by me this 20th day of June, A. D. 1884.

THOS. ANGELL.
